UNITED STATES PATENT OFFICE

97,077

DESIGN FOR AN INKWELL

Hermann Langen, Cologne, Germany

Application June 29, 1934, Serial No. 52,381
In Germany March 16, 1934

Term of patent 14 years

To all whom it may concern:

Be it known that I, Hermann Langen, a citizen of Germany, residing at Cologne, Germany, have invented a new, original, and ornamental Design for an Ink Well, of which the following is a specification, reference being had to the accompanying drawing, forming part thereof. The figure is a perspective view of an ink well showing my new design.

The characteristic feature of my design is the upward curvature underneath which divides the ink bottle into a feeding part and a tank reservoir, the bottoms of both of these elements lying in the same plane.

I claim:

The ornamental design for an ink well, substantially as shown and described.

HERMANN LANGEN.
